STUCCO BASE

Filed May 16, 1928

INVENTOR,
J. W. WRIGHT.
By *Arthur P. Smith*
ATTY.

UNITED STATES PATENT OFFICE

JAMES W. WRIGHT, OF LOS ANGELES, CALIFORNIA

STUCCO BASE

Application filed May 16, 1928. Serial No. 278,140.

My invention relates generally to building material, and more particularly to a stucco base and the principal object of my invention is to provide a base or anchoring member that performs the functions of a cover or sheathing, and at the same time, carries furring material, preferably expanded metal or the like, which serves as an anchorage for stucco plaster or the like self-hardening material that is applied to the base.

Further objects of my invention are to generally improve upon and simplify the construction of the existing forms of base or anchoring members that receives outer coatings of stucco, plaster or the like, to provide a covering base that is relatively simple in construction, inexpensive of manufacture, and which may be easily and quickly applied to building walls or other structures that are to be covered with stucco or the like.

A further object of my invention is to provide a stucco base member that is constructed so that it may be laid in courses after the manner of rough shingles with the exposed portions of the base members being overlaid with reticulated furring material, such as expanded metal, wire netting or the like, with portions of said furring material interposed between layers of felt or the like, which form the bodies of the base members, and these interposed portions of the furring material being located so as to receive the nails that fasten the base members to the building wall or other structure.

Further objects of my inventions are to provide a stucco base which, when properly laid, provides an air and moisture-proof covering, and which base will permit the coating of stucco or the like to expand and contract to a considerable degree, without cracking.

With the foregoing and other objects in view, my invention consists in certain novel features of construction and arrangement of parts that will hereinafter be more fully described and claimed and illustrated in the accompanying drawing, in which—

Fig. 1 is an elevational view of a stucco base member constructed in accordance with my invention.

Fig. 2 is a cross section taken on the line 2—2 of Fig. 1.

Fig. 3 is a cross section taken on the line 3—3 of Fig. 1.

Fig. 4 is a cross section taken on the line 4—4 of Fig. 1.

Fig. 5 is an elevational view of a number of the stucco base members assembled or laid in courses to form a continuous furred surface for the reception of stucco, plaster or the like.

Fig. 6 is an enlarged vertical section taken on the line 6—6 of Fig. 5.

Referring by numerals to the accompanying drawings, 10 designates the inner or rear layer of the body of the base, the same being preferably formed of felt paper or the like, and the length of which is substantially greater than the width, and overlying the upper front portion of the back layer, is a front layer 11 of the felt paper, or the like, that is secured to the back layer by a suitable adhesive, preferably asphalt. The width of the front layer 11, is equal to the width of the rear layer, but the length of said front layer is somewhat less than said rear layer, so that the lower edge of the front layer terminates several inches above the lower edge of the rear layer.

Overlying that portion of the rear layer 10, below the lower edge of the front layer 11, is a substantially rectangular section 12 of self-furring material, preferably expanded sheet metal, woven wire or the like, and the upper edge of this furring metal extends upwardly a short distance between the layers 10 and 11 of felt, and this interposed portion of the metal is secured to the layers 10 and 11 in any suitable manner, preferably by means of asphalt.

If desired, the furring metal may be bent outward a short distance just below the lower edge of the front layer 11, thus forming a transversely disposed shoulder against which the lower edge of an overlying base member is arranged when the members are laid in courses on a building wall or the like.

In laying the base members constructed as just described, a number of said members are arranged side-by-side to form a course,

and by means of nails driven thru said members just above the lower edges of the front layers 11, said members are firmly secured to the sheathing or building structure. Inasmuch as the upper portions of the furring metal extend beneath the lower edges of the front or outer layers 11, the interposed sections of wire serve as firm anchorage for the nails that are utilized in securing the base members to the building structure, and when the succeeding course of base members are applied to the first laid course, the lower portions of the second course of said members overlie the heads of the nails utilized in fastening the members of the first course, and this arrangement is continued until the area to be covered with the members is entirely overlaid.

In laying the base members, the joints between the succeeding courses are broken after the manner of broken joints between shingles, tile and the like.

When the base members have been properly applied to the surface that is to be covered, the sections of furring metal 12 present a practically continuous furred surface that receives the stucco, plaster or other hardening material, and portions of the latter, when applied, pass thru and "key" behind the metal and thus, the finishing coat of self-hardening plastic material is very securely anchored to the base members, and an air and moisture-proof covering surface is provided.

Even tho the stucco or plaster should become broke, the overlaid double layers of felt papers that form the bodies of the base members provide an air and moisture-proof covering for the underlying building structure, thus insuring a warm, dry and comfortable interior.

It is a well established fact that varying temperatures will cause, stucco and the like to expand and contract, and if no provision is made to permit such expansion and contraction, the structure, plaster or cement will crack and break. In my improved base, provision is made to permit expansion and contraction of the stucco, cement or plaster outer coating, for the nails that are utilized in securing the base members to the building structure pass thru those portions of the furring metal that are spaced apart from the portions that receive the stucco or plaster coating, and thus, the layers of felt and the interposed furring material immediately surrounding the nails provide a cushion base that will yield readily under varying degrees of temperature, thus permit the coating of stucco, cement or the like, to move for a limited distance, as a result of expansion or contraction, and which action takes place without cracking or checking.

Practically all stucco or cement walls will sweat as a result of varying temperature con-

ditions, for instance, relatively cool nights and warm or hot days, and such conditions produce, by condensation, moisture on the inner surface of the body of stucco of cement, and unless the cement or stucco is laid on an absolutely moisture-proof base, this condensation will pass thru to the inside plaster, thereby causing dampness on the surface of said plaster and consequent injury to the interior decorations.

In my improved base, the double layers of the overlaid felt sheets that form the bodies of the base, effectually prevents moisture passing from the stucco body inwardly, to the interior plaster and at the same time, effectually prevents the inward passage of air and consequently, provides a warm interior.

Thus, it will be seen that I have provided a stucco base that is relatively simple in construction, inexpensive of manufacture, capable of being easily and quickly applied for use and very effective in performing its intended functions.

It will be understood that minor changes in the size, form and construction of the various parts of my improved stucco base may be made and substituted for those herein shown and described without departing from the spirit of my invention, the scope of which is set forth in the appended claims.

I claim as my invention:

1. As a new article of manufacture, a stucco base comprising an underlying sheet of fibrous material, an overlying sheet of fibrous material secured to the upper portion of said underlying sheet, so that a portion of said overlying sheet extends beyond the lower edge of the underlying sheet, a section of self-furring metal secured to, and overlying that portion of the underlying sheet that projects beyond the lower edge of the overlying sheet and the exposed portion of which section of metal occupies a plane parallel with and in front of the front face of the overlying sheet.

2. As a new article of manufacture, a stucco base comprising an underlying sheet of fibrous material, an overlying sheet of fibrous material secured to the upper portion of said underlying sheet, so that a portion of said overlying sheet extends beyond the lower edge of the underlying sheet, a section of self-furring metal secured to, and overlying that portion of the underlying sheet that projects beyond the lower edge of the overlying sheet, the exposed portion of which metal occupies a plane parallel with and in front of the plane occupied by the front face of the overlying sheet, and a portion of which self-furring metal projects beneath the lower edge of the overlying sheet of fibrous material.

3. As a new article of manufacture, a stucco base comprising a substantially rectangular sheet of fibrous material, a substantially rec-

tangular sheet of fibrous material secured to and overlying the upper portion of said first mentioned section of fibrous material, the lower edge of which overlying sheet of material terminates above the lower edge of the underlying sheet of fibrous material, a section of reticulated metal secured to and overlying that portion of the underlying sheet of material that projects below the lower edge of the overlying sheet of material and the exposed portion of which metal section being spaced apart from and lying parallel with the front face of the underlying sheet.

4. As a new article of manufacture, a stucco base comprising a substantially rectangular sheet of fibrous material, a substantially rectangular sheet of fibrous material secured to and overlying the upper portion of said first mentioned section of fibrous material, the lower edge of which overlying sheet of material terminates above the lower edge of the underlying sheet of fibrous material, a section of reticulated metal secured to and overlying that portion of the underlying sheet of material that projects below the lower edge of the overlying sheet of material, the exposed portion of which metal section occupies a position spaced apart from and parallel with the adjacent face of the underlying sheet of fibrous material, and a portion of which reticulated section of metal extends beneath the lower portion of the overlying sheet of fibrous material.

5. As a new article of manufacture, a stucco base comprising an underlying section of fibrous material, a section of self-furring reticulated metal secured to and overlying the lower portion of the front face of said section of fibrous material, an overlying section of fibrous material secured to the upper portion of said underlying section of fibrous material and which section of metal is bent to form a transverse shoulder immediately adjacent to the lower edge of the overlying section of fibrous material so that the exposed portion of the metal occupies a plane in front of and spaced apart from the adjacent face of the underlying section of fibrous material.

6. As a new article of manufacture, a stucco base comprising an underlying section of fibrous material, a section of self-furring reticulated metal secured to and overlying the lower portion of the front face of said section of fibrous material, and an overlying section of fibrous material secured to the upper portion of said underlying section of fibrous material, the lower portion of which overlying section of fibrous material overlies the upper portion of said section of self-furring metal and said section of metal being provided with a transverse shoulder immediately below the lower edge of the overlying section of fibrous material so that the exposed portion of the metal occupies a plane in front

of and parallel with the front face of the underlying section of fibrous material.

In testimony whereof I affix my signature.

JAMES W. WRIGHT.
